UNITED STATES PATENT OFFICE.

EUGENE BRETNEY, OF INDIANAPOLIS, INDIANA, ASSIGNOR OF TWO-THIRDS TO EDWARD H. SCHMIDT AND L. P. ROTHLCHILD, OF INDIANAPOLIS, INDIANA.

STOKER FOR FURNACES.

No. 864,946.

Specification of Letters Patent.

Patented Sept. 3, 1907.

Application filed February 18, 1907. Serial No. 358,090.

To all whom it may concern:

Be it known that I, EUGENE BRETNEY, a citizen of the United States, residing at Indianapolis, in the county of Marion and State of Indiana, have invented 5 certain new and useful Improvements in Stokers for Furnaces, of which the following is a specification.

This invention relates to improvements in grates for furnace fires for steam heating plants, and similar purposes, and the object of the invention is to provide end-10 less traveling grate-bars mounted obliquely to the horizontal, and sloping downwardly from front to rear of the fire-box, said grate-bars being mounted on a track on a suitably wheeled truck to permit of ready withdrawal from under the boilers for cleaning and repairs.

15 Another and important object of the invention is to provide a screw-conveyer for carrying the fuel from front to rear of the grate-bars, underneath the latter, and screw conveying means for elevating the fuel and discharging it upon the lower rear end of the traveling 20 grate-bars.

I accomplish the objects of the invention by the mechanism illustrated in the accompanying drawings, in which—

Figure 1 is a detail in vertical section of a fire-box 25 equipped with my invention, the view being taken on a plane extending from front to rear of the fire-box at right angles to the furnace-front. Fig. 2 is a detail in vertical section on the line 2—2 of Fig. 1, and Fig. 3 is a horizontal section of one of the vertical screw-convey-30 ers.

Like characters of reference indicate like parts throughout the several views of the drawings.

5 represents a boiler for generating steam, of any usual and suitable construction, here shown as a tubular boiler, and 6 represents the brick-setting supporting same and forming the walls of the fire-box 7. 8 is a track extending horizontally under the fire-box 7, and 9 is a truck having the wheels 10 resting upon the track 8. This construction permits the truck 9 to be moved 40 on the track in and out under the fire-box 7.

12 is a horizontal upper shaft and 13 a parallel lower shaft, both of which are mounted in journal-boxes supported by the upwardly extended sides of the truck 9.

45 14 are sprocket-drums mounted upon each of the shafts 12 and 13, and 15 is a traveling or chain grate forming an endless apron which passes around both of the drums 14. The shaft 12, being higher than the shaft 13, causes the upper end of the traveling grate 15 to be elevated. The upper shaft 12 has a pulley 16 (shown in 50 dotted lines in Fig. 1), which is driven from any suitable motor by the belt 17.

Located under the traveling grate 15 are a series of horizontal conveyer-troughs 18, the number depending upon the width of the fire-box, which may vary with 55 the size of the boilers. Each of these conveyer-troughs

is provided with a longitudinal screw-conveyer 20, the front end of the shaft of which carries the bevel gear wheel 21.

22 is the oblique bottom of a coal-chute located under the traveling grate 15 and into this chute the 60 coal to be used as fuel will be dumped, and will be deposited by gravity upon the conveyers 20 in the troughs 18. Supported by the truck 9 and located at the rear of each of the troughs 18 are the inverted conical, vertical, coal chutes 24. These have inlet 65 openings 25 at their lower ends at diametrically opposite sides of the chutes. Each of these vertical chutes 24 have their lower ends located in the extensions 26, of the chutes 18. The bottoms of the extensions 26 are oblique, and slope downwardly from 70 the chutes 18 so as to carry the fuel from the ends of the latter, by gravity, to the openings 25 in the vertical chutes 24. The upper ends of the chutes 24 terminate above the lower inner ends of the traveling grate 15, and have the forwardly oblique deflecting 75 plate 30 to direct the discharge from the chute in the direction of the grate-bar. The upper end of the chute 24 also has the oblique plate 31, down which the fuel discharged from said chute will travel by gravity and will be deposited upon the traveling 80 grate 15. Located within the chute 24 is the vertical screw-conveyer 33, the wings of which increase in width or radius from the lower end of the chute outwardly to correspond with the increase in diameter of the conical walls of the chute. The object in making the walls of the chute 24 of gradually increasing diameter from lower to upper end of the chute is to avoid the packing of the fuel within said chute; and to prevent the fuel contents of the vertical chute from 85 being carried around by the conveyer-screw without advancing upwardly, the walls of the chute will be provided with the longitudinal corrugations 34. The walls of these corrugations, on the side toward which the conveyer is traveling, will preferably be more abrupt than the other wall of the same corrugation so 90 as to more positively resist the motion of rotation imparted by the screw-conveyer.

95 Mounted on the truck 9 are the horizontal shafts 38. These shafts will be geared together by any suitable means, here shown as by means of a link belt 40, 100 which connects the sprocket-wheels 41 mounted on each of said shafts 38.

105 42 is a ratchet-wheel here shown as mounted on the forward end of one of the shafts 38.

43 is a yoke mounted on the shaft 38, over the sprocket wheel 42, and having a lever extension by means of which the yoke is reciprocated.

44 is a pawl, carried by the yoke, which engages the teeth of the ratchet-wheel 42 so as to move the ratchet-

wheel forward by the reciprocatory movement of the 110

yoke and its lever. The swinging movement of said lever and yoke will be imparted in any suitable manner.

Carried by the truck 9 and mounted at right angles to the shafts 38 are an equal number of vertical shafts 50. Mounted on the upper end of each shaft 50 is a beveled pinion 51 meshing with the beveled wheel 21 on the shaft of the conveyer 20, and mounted on the lower end of each shaft 50 is a bevel-wheel 53 which meshes with a like bevel wheel 54 on the adjacent shaft 38. The inner end of each shaft 38 carries a bevel wheel 56 which meshes with a bevel wheel 57 on the lower end of the shaft of the adjacent conveyer 33.

By the above construction, the rotation of shafts 38 will impart a simultaneous rotary movement to both screw-conveyers 20 and 33.

My invention is capable of variation in many of its details of construction without departing from the spirit of this invention, and I therefore do not desire 20 to be limited to the exact device shown, but

What I claim as new and wish to secure by Letters Patent of the United States, is—

1. In a furnace, a grate, an approximately vertical fuel-chute at the rear of the grate having a top discharge upon said grate the interior walls of said chute having longitudinal channels, a conveyer-screw rotating in said chute, a second chute under the grate discharging into the lower end of the vertical chute and a conveyer-screw rotating in said second chute.

2. In a furnace, a grate, an upright fuel chute at the rear of the grate having a top discharge upon said grate, the diameter of said chute increasing gradually from bottom to top, the interior walls of said chute having longitudinal channels, a conveyer-screw rotating in said chute and means for supplying fuel to the lower end of said chute.

3. In a furnace, a grate, an upright fuel-chute at the rear of the grate having a top discharge upon said grate, the diameter of said chute increasing gradually from bottom to top, inside longitudinal channels in said chute having angular walls one of which is in a plane approximately

radial with relation to the center of the chute, a longitudinally disposed revoluble conveyer-screw in said chute rotating toward the radially disposed walls of the longitudinal chute-channels, and means for delivering fuel to the bottom of said chute.

4. In a furnace, a movable grate sloping upwardly from rear to the front of the fire-box, an upright fuel chute discharging upon the rear of the grate said chute having a gradual increase in diameter from the bottom to the top with annular longitudinal inside corrugations, a conveyer-screw rotating in said chute said screw standing longitudinally of the chute and having blades increasing in width proportionately with the increased diameter of the chute said chute having bottom inlets, a second chute under the grate discharging into the lower end of the upright chute, a conveyer-screw rotating in the second chute, and means for advancing the grate to gradually carry the fuel from back to the front of the fire-box.

5. In a furnace, a truck mounted on wheels a grate mounted on said truck, an upright fuel-chute at the rear of the grate having a top discharge upon said grate and carried by said truck, a conveyer-screw rotating in said chute, a second chute under the grate carried by said truck and discharging into the lower end of the vertical-chute 65 and a conveyer-screw in said second chute.

6. In a furnace, a fire-box, rails forming a track on the floor below the fire-box and extending out forwardly of the furnace, a truck, flanged wheels on said truck whereby the latter is mounted on said track, a movable grate sloping upwardly from rear to front of the fire-box and mounted on said truck, an upright fuel chute at the rear of the grate having a top discharge upon said grate, said chute increasing gradually in diameter from bottom to top, a conveyer-screw rotating in said chute, a second chute under the grate carried by said truck and discharging into the lower end of the upright chute, a conveyer-screw rotating in the second chute, and means for advancing the grate to gradually carry the fuel from the back to the front of the fire-box.

In witness whereof, I, have hereunto set my hand and seal at Indianapolis, Indiana, this, 8th day of February, A. D. one thousand nine hundred and seven.

EUGENE BRETNEY. [L. S.]
